DESIGN FOR A HANDBAG

Louis J. Coblenz, New York, N. Y.

Application August 23, 1938, Serial No. 79,497

Term of patent 3½ years

To all whom it may concern:

Be it known that I, Louis J. Coblenz, a citizen of the United States of America, residing in the city of New York, county of New York, and State of New York, have invented a new, original, and ornamental Design for a Handbag, of which the following is a specification, reference being had to the accompanying drawing, forming part thereof,

Fig. 1 is a front view of a handbag showing my new design.

Fig. 2 is a plan view thereof.

Fig. 3 is an end elevational view.

I claim:

The ornamental design for a handbag, substantially as shown.

LOUIS J. COBLENTZ.
